UNITED STATES PATENT OFFICE.

FENTON G. FOSTER, OF WAKE COUNTY, NORTH CAROLINA.

IMPROVEMENT IN TYPE-SETTING MACHINES.

Specification forming part of Letters Patent No. **149,647**, dated April 14, 1874; application filed February 11, 1874.

To all whom it may concern:

Be it known that I, FENTON G. FOSTER, of the county of Wake and State of North Carolina, have made an invention of certain new and useful Improvements in Machines for Setting Printer's Type; and that the following is a full, clear, and exact description and specification of the same.

The object of this invention is to render the machine on which I have heretofore procured Letters Patent of the United States more efficient in setting printer's type, and in that form now set by hand. This invention consists in certain devices for this purpose; and, in order that these improvements may be fully understood, a machine is herein represented by the accompanying drawings, which I shall now proceed to describe, reference being had to said drawings and the letters marked thereon.

Figure 1 represents a perspective view; Fig. 2, a sectional view; Fig. 3, a perspective view of the device whereby the font of letters is changed; Fig. 4, an enlarged view of finger acting in its recess, with its accompanying spring, aperture, stop, and inlet to groove; Fig. 5, a separate and enlarged view of device for announcing when any particular letter is exhausted; Fig. 6, an enlarged perspective view of improved type-box. Fig. 6^a is a longitudinal section of the same; Fig. 7, a separate view of device for disconnecting the keys with the fingers of any particular font-box, so that another of a different font may be substituted; Fig. 8, an enlarged and separate view of device for connecting the rods and keys; Fig. 9, a separate view of the stick-board and its accompaniments.

The case A, Fig. 1, is placed on top of case B, as described in patent hereinbefore referred to. This case A has its front formed of two separate pieces, *a b*. The upper part is also provided with fingers, recesses, and grooves. These fingers operate upward from their respective axes, thereby throwing the apertures from which the type is supplied to the fingers in the upper part of the recesses, instead of the lower, as heretofore. By this arrangement the type-boxes are thrown above the axes of said fingers, and the wires connecting the keys and said fingers, instead of running through the

type-boxes and connecting with said fingers above said type-boxes, as heretofore, are made to connect below; thus rendering the machine more practicable, easier to change the boxes holding the type, and connect and disconnect the wires. The fingers *x x* are provided with springs *o*, whereby they are more certainly and effectually thrown back to their former positions, occupied before the key was depressed. These fingers have also their front under edge beveled, so that they are thinner than the type which any particular finger may operate, thus preventing inefficiency in striking out its type, on account of wear through long use, and also causing it to strike but one type at a time. The recess is further provided with a stop, *c*, (best shown in Fig. 4,) whereby the finger is prevented from moving farther than is necessary to place the type in its particular groove, and beyond the action of the type-box spring, the finger being so formed, as represented in said Fig. 4, that, while under influence of the key it entirely covers the aperture *n*, it can pass no farther than necessary to accomplish said object. This stop is formed by continuing that side of each groove next its respective finger up to or toward the lower point of said aperture, which connects the type-box with its particular recess; and thereby also forming a good base for securing the before-mentioned spring *o*. This spring may be fastened on the inside of the axis of each finger, or onto the lever operating the finger from the inside; but, in every case, it acts in conjunction with the springs placed under the front ends of the keys of the key-board when the pressure is removed, and thus more certainly throws back the finger to the position occupied before the key was depressed. The top board *a* is also made in a better form (represented in Fig. 3) for holding the several type-boxes, one of which, *d*, is here represented placed in its groove and ready to be slipped down to its proper position while feeding out type to the fingers. Each of these type-boxes is provided with a handle, *e*, whereby it can be more readily removed when empty. This top board *a*, or, as I designate it, "font-changer," is also provided with handles *ff*, one at each of its ends, by means of which the whole font-changer, with its several boxes, fingers, springs,

glass, and type, may be easily removed. The glass covering the whole of the front part of the box A, Fig. 1, has been divided into two pieces, instead of one, thereby giving greater beauty to the instrument, besides rendering the danger of breaking the same less, while each plate remains covered with its particular glass. These respective glasses may be liable to spring when covering a full plate of a large working instrument; in that case they must be divided into a number of pieces, for it is absolutely necessary that the glass should fit the grooved board closely, or else the necessity of each groove being thus formed into a perfectly closed tube would not be satisfied. The inclined plane $g g$ is extended downward and forward, through the keys of the keyboard, onto the stick-board, thereby making it more convenient for the operator to manipulate, if necessary, the line of type set. This inclined plane is also provided with feeders $s s$, (best shown in Fig. 2,) and is thus better connected with the plates placed one behind the other. Each of these feeders is provided at its lower end with a brake, u , suitably balanced, so that any type can readily pass under the same by the mere force gained by falling down its own tube, the brake readily conforming itself to any particular and every thickness of the types. This brake is also designed to retard the before accelerated motion of the types, thereby insuring greater certainty in falling into the stick O', Fig. 2, with their nicks in the right direction. At the points $h h$, or where the feeders connect with their respective grooved plates, it is designed to place other brakes, somewhat similarly made, whereby the tube formed by the glass and board may be continued into the feeder, and, by means of said brakes, made adjustable to any sized type of that particular font then operated on; for the groove in this feeder, being necessarily large enough to permit the thickest type of any plate to pass easily thence into the inclined plane, must, on this account, render the smaller type—an "i," for instance—more liable to change the relative position of its nick when passing round this curve. But if the upper point v of said brake u is made of such a shape as to operate in the curved feeder where it joins the glass-covered plate, there will be no necessity for a second brake at this point. And it will furthermore possess the advantage of rendering the clogging of the type more difficult while passing through onto the inclined plane $g g$; for, in that case, a type passing under the lower end k of the brake u will necessarily depress its upper end v , thereby closing the groove to the exit of another type from the plate until the first type shall have fully passed onto the inclined plane. This brake u is pivoted in such a position that its lower end k will rest in the groove $i i$ of the inclined plane $g g$ at the point where each type from the feeder will fall into said groove, thus forming a wedge-shaped recess, into which the type must fall, and thereby again the better insuring the relative posi-

tion of the nick. It will be observed that the brake operating at the lower point of the feeder connected with the front plate is thus placed directly over the point where the plates, ranged one behind the other, connect by means of the inclined plane. At this point the type from the front plate necessarily experiences a considerable jar in passing, which, if not for said brake, might cause the derangement of its nick. The rod m , Fig. 7, which connects the keys with the lever, operating and fastened on the inside of the finger, is formed at its upper end into a loop, p , which, while it permits the easy disconnection of said keys from their fingers, as herein more fully described, at the same time acts as a knee-joint while operating said levers, so that said levers are permitted to describe the small arc required whenever the keys are depressed, the movement of said levers being thus rendered easy and complete, which could not be accomplished by a permanent and solid connection. The lower end of this rod is fastened into a screw, Fig. 8, having a similar loop, and which screw is inserted into the key. This screw permits the rod to be shortened or lengthened, if required, and by its connection with the rod permits said rod to move backward or forward, or from side to side. The frame $r r w w$, Fig. 7, operates inside of the case A, Fig. 1, the ends $r r$ projecting from the same, as shown. On this frame are placed loops or eyelets $y y$, through which the rods m pass, and by which they are held in position when thrown off the finger-levers l , Fig. 2. Now, if it is desired to change the font of type, the ends $r r$ are seized by the operator, pushed back, and every rod is thrown off its finger, and the keys become entirely disconnected from the font-changer. The font-changer, Fig. 3, is now easily lifted out by its handles, as already described, and another substituted, when, the frame being pulled back to its former position, the loops p of the rods m at once engage the levers l of the fingers of the new board, and the machine is ready for operating the new font of letters.

These font-changers, as I have before said, hold the boxes containing the supply of type, one of which type-boxes is represented at Figs. 6 and 6'. On the front end of this box is a device, c , moving on a pivot, q^2 . When this box is filled with type the device is held in the position shown in Fig. 6, thus preventing the spring-follower from ejecting the type, by having its side directly over and partially covering the front opening of the box. But when it is placed in the font-changer, Fig. 3, and in its particular groove, this groove causes the slot therein to correspond with that of the type-box, so that the type are free to be thrown forward within range of the movement of the finger. The top of the front end of this type-box is left closed up, as at r^2 , by which means the types are prevented from sliding upward while the box is being depressed fully into its position by means of the handle e in Fig. 3. On the spring of each type-box there is fixed

a follower, t , of the form shown, one part of which, s^1 , projects above the box, and forms a convenient catch for the finger when the spring is to be depressed into the head of the type-box. In the rear end of this box there is a notch, q , into which the point of the follower s^2 catches whenever the spring is depressed, thereby rendering said spring inactive while the box is being filled. The upper end s^1 of this follower answers another purpose, which I shall now describe. On the top of the machine, and fully shown in the perspective view, Fig. 1, is an annunciator, o^1 , which is sounded by a hammer, o^2 . This hammer is secured to an axle, a^3 , on the opposite side of which is a wire, which catches into the little recess b^2 , cut into the bar c^2 . This bar is fixed on the rear ends of two levers, $x^1 x^1$, which move on fulcrums near their centers. On the front ends of these levers $x^1 x^1$, at the points $y^1 y^1$, is inserted a wire or rod, bent at right angles at each end. These ends being inserted in the ends of the levers, at $y^1 y^1$, the rest of the wire y^1 hangs down and inside of the case A at its upper part, and above the font-changers. Now, when a box filled with type has been placed in its groove in this font-changer, Fig. 3, and pushed down to its position, a device represented in Fig. 5, made of the same length of the type-box, is placed immediately on and above it, and in this same groove. This device (and there is one for every type-box) has a lever, b^4 , hinged on its top, and operating by means of a spring, f^2 . On the front end of this lever a wire, u^2 , is fastened, the lower end of which, provided with a hook or other suitable device, l^5 , fastens itself, when the lever b^4 is depressed, onto the little catch x^2 . Now, when the last type falls out, the front end of the follower t , Fig. 6, is thrown against the glass a , and the point s^1 comes in contact with the hooked end of the wire u^2 , and throws it from its fastening x^2 . The lever b^4 , flying up by the force of the spring f^2 , strikes against the wire y^1 , fastened at the points $y^1 y^1$, Fig. 1, thus raising the front ends of the levers $x^1 x^1$, and, depressing the bar c^2 , disengages the wire on the axle a^3 from its fastening in the notch b^2 , and the hammer o^2 , by means of the spring m' , strikes the bell o^1 , and the box is thereby known to be empty. By raising the top s^5 , the particular box is recognized, and is lifted out and replaced by a full one. The stick-board, Fig. 9, works under the bottom of the case B like a drawer, and is easily detached therefrom, if required. When a type comes down the inclined plane $g g$ it falls into a recess, b^3 , formed by the stick-follower h^1 , and the front part of the inclined plane g . The packer l^1 is now pulled forward by means of the handle l^2 , operating the lever x^3 , and the type just dropped is moved forward its own thickness toward the front of the stick-board, carrying the follower h^1 before it; one object of this packer being to preserve this recess against being packed with type, and give to each descending type a space sufficient to

set itself upright in the stick. When the spring x^5 is relieved of the force communicated by means of the rod and handle l^2 , it operates on the lever x^3 , and causes it to draw the packer l^1 back to its former position, the connecting-rod x^2 making this motion easy and certain. This packer can, however, be operated in a more convenient manner by a pedal attached to a suitable crank. As every type falls into the stick, the follower h^1 is continually moved forward until it reaches the front side of the stick-board upon the completion of every line, and there fills the little recess b^3 , which disengaging the rod a^2 from its rest therein, the hammer o^3 is thereby caused to sound the annunciator o^4 , and the line is known to be completed. This hammer is operated by a spring, s^3 . (Best seen in Fig. 1.) The setting-rule u^2 is now thrown back, the driver pushed forward by means of its head a^4 , and the line is discharged into the galley D, leaving the machine ready for setting another line. The form of the follower h^1 is that of a right angle, as best represented at o^1 , Fig. 2, and works under the lower front end of the inclined plane $g g$, and immediately under the packer l^1 ; the bottom of the inclined plane $g g$, at its front edge, being grooved, for the purpose of permitting the packer to slip back and forth with ease. By making the front side of this stick-board l^1 to move backward or forward, by screws or otherwise, the length of the line may be increased, as desired. This stick-board is also provided with boxes $h^2 h^2$, for holding spaces used in justifying.

I claim as my invention, and wish to secure by Letters Patent—

1. The finger x , when made substantially as represented, so that, in conjunction with the stop c , it is permitted to move only so far as to place the type fairly in its tube.

2. The finger x , when working upward from its axle, so that, in conjunction with the type-box d , feeding into the upper instead of the lower part of the recess, the rod m , connecting a key of the key-board with a finger-lever, l , is connected with said lever below the type-boxes, substantially as represented and described.

3. The upper part a of the front board $a b$ of the case A, constructed in a separate piece from the lower part b , and so connected with the type-boxes $d d$ that, by means of the handles $f f$, all the type-boxes can be removed at once, and by the same motion that removes the board, and another of similar make containing a different font substituted, substantially as represented and described.

4. The combination of a removable type-box, d , and grooved board a , said type-box operating in the rear of said grooved board, and in conjunction with a finger, x , substantially as represented and described.

5. The detachable rods m , constructed as described, in combination with the sliding frame $r r w w$, arranged substantially as and for the purposes set forth.

6. The device C, having an opening corresponding to that of the type-box *d*, and pivoted thereto, substantially as represented and described.

7. The follower *t*, when made as represented and described, and used in connection with a type-box, *d*, and its spring, for the purpose of depressing said spring while filling, and, at the same time, serving as a trip to the wire *u*² when the last type is used, substantially as represented and described.

8. The combination of device, Fig. 5, annunciator *o*¹, hammer *o*², axle *a*³, bar *e*², levers *x*¹ *x*¹, wire *y*¹ *y*¹, and follower *t*, and type-box *d*, or their substantial equivalents, when used for the purpose of announcing a type-box

empty, substantially as represented and described.

9. The combination of slot *q*, follower *t*, point *s*², type-box *d*, and type-box spring, when used for the purpose of retaining said spring when depressed, substantially as represented and described.

10. The stick-follower *h*¹, when made as described, and working directly under the packer *l*, substantially as and for the purposes set forth.

FENTON G. FOSTER.
